UNITED STATES PATENT OFFICE.

ROBERT CECCHINI, OF SPRINGFIELD, MASSACHUSETTS.

AUTOMATIC RAILWAY-TRAIN STOP.

1,175,704.

Specification of Letters Patent. Patented Mar. 14, 1916.

Application filed May 11, 1915. Serial No. 27,296.

To all whom it may concern:

Be it known that I, ROBERT CECCHINI, a British subject, and resident of Springfield, in the county of Hampden and State of Massachusetts, have invented certain new and useful Improvements in Automatic Railway-Train Stops, of which the following is a full, clear, and exact description.

This invention relates to an automatic train stop of the class or kind which is operative when the train runs past a signal set at danger, or into a block while another train is in the same block, to operate stopping or controlling devices of the locomotive, such, for instance, as the throttle valve, the engineer's air brake valve, the valve controlling track sanding supply, or simultaneously all of such valves, and also, if desired, as an auxiliary brake mechanism which becomes operable in cases when by failure of the usual air brake apparatus the auxiliary brake may be set.

An object of the invention is to provide improved apparatuses or appliances for the efficient and reliable stopping of the train under danger conditions, by the utilization, under normal conditions, of an automatically controlled source of air under pressure.

Another object is to so adapt the apparatus, as, in cases of emergency, to be operable by steam from the boiler in cases where the air supply fails or becomes ineffective by lowered pressure thereof.

In the apparatus as here disclosed, the air operable as the motive agent for actuating the train controlling devices in cases of danger, automatically controls the steam to be used in cases of emergency, that is the steam supply pipe leading from the boiler is normally shut by a valve or cock, but which valve on the failure of the supply of the air as the motor agent is opened so that the steam will perform the same office as that designed for the air.

Other objects of the invention are to provide improved means for the electrical control of an electric motor carried on the locomotive and which motor operatively controls the valve for the motor fluid, air or steam as the case may be which actuates the train controlling devices.

Another object is to generally simplify and improve the train stopping apparatus. The invention is described in conjunction

with the accompanying drawings and is set forth in the claims.

In the drawings:—Figure 1 is a general diagrammatic view of the device and such other parts of the locomotive, tracks, signaling apparatus, etc., as are used in connection with the device. Fig. 2 is a plan view of the ordinary railroad track showing the signal posts at intervals along the track and also the sub-rail located near each signal post. Fig. 3 is an end view of a locomotive on its track with the signal post and sub-rail shown in their relative positions. Fig. 4 is a detail of the switching mechanism, etc., which is located in the engineer's cab.

The operation of the semaphore arm of the signal is controlled by means of electricity supplied by a suitable battery 2 from which an extra circuit is taken off which is controlled by a switch 3 so designed that when the semaphore arm is set at danger the circuit is closed and the current is free to flow through wire 4 to sub-rail 5.

At a convenient point on the locomotive is attached a collecting or contacting wheel 6 which rolls over the top edge of sub-rail 5 and to which is connected a wire 7 running to a magnet 8 and from there returning through a wire 9 to two small contacting wheels 10 which roll upon the main rails 11. A wire 12 connects these rails back to the battery 2 completing the circuit.

When the signal is set at danger and the locomotive comes opposite the sub-rail 5, the current flows from the battery 2 through switch 3, wire 4, rail 5, contactor wheel 6, wire 7, magnet 8, wire 9, either one of the wheels 10 to rail 11 and back through wire 12 to battery. When this current flows through magnet 8 this magnet is demagnetized or neutralized and current from battery 13 flowing through switch 14 and magnet 15, actuates the pivoted switch 16 which closes the gap between contacts 17, 17, and allows current to flow from battery 18 through contacts 17 to motor 19 and return.

When the motor revolves a pinion on its shaft acts with a rack to draw a rod 20 which opens valve 21, allowing air at a pressure of about 130 lbs. to flow from main reservoir A through pipe 22, check valve 23 to pipe 24 and branching off into three cylinders 25, 26, and 27, which act to close the

throttle 28, operate the brakes through the engineer's valve 29 and apply the air sander valve 30 respectively.

If for any reason the pressure of air in the main reservoir falls below 60 lbs., the spring 31 back of piston 32 in cylinder 33 overcomes the air pressure on the other side of piston and opens valve 34, allowing steam from the boiler to pass through pipes 35 and 36 into pipe 22, thence through valve 21, if open, and then into pipe 24 and operating above mentioned cylinders 25, 26, and 27, as described above.

The check valve 23 is for the purpose of keeping the steam in pipe 22 from getting into the main reservoir.

When steam is allowed to pass through valve 34 and into pipe 36 it also passes through pipe 37 into additional brake cylinder 38 which applies the brakes upon the locomotive.

Ordinarily and for protracted periods, without exception, the operation of the engineer's brake valve will be adequate to set the brakes.

The provision of the means including the steam cylinder 38 hereinabove just referred to is to be considered as a steam operated emergency brake to become automatically operable in the very rare cases when the air supply would fail or become ineffective for the usual and expected operations.

The pin 39 on end of pinion of motor 19, Fig. 4, is for a crank to be applied so the engineer can return the rack and its rod 20 and valve 21 to the normal position.

Magnet 8 has a steel core and is, therefore, a permanent magnet and when there is no current in the coil of said magnet the magnetism in this core is strong enough to hold pivoted switch 16 from contacts 17 against the action of magnet 15.

If current does flow through magnet 8 the magnetism in the core is neutralized and then magnet 15 becomes the stronger of the two and attracts the other end of switch 16.

The switch will remain in this position until the engineer opens switch 14 which causes magnet 15 to become inoperative and as the current which flowed through magnet 8 has ceased the permanent core of said magnet will again attract switch 16 to its normal position as shown, after which the engineer closes switch 14 restoring the energy to magnet 15. The reason that magnet 15

cannot attract switch 16 is because of the large gap and also the counter attraction of magnet 8.

Port 40 Fig. 4, is to exhaust the air from cylinders 25, 26, 27, or to exhaust steam from cylinders 25, 26, 27, and 38 if steam is used, when valve 21 is returned to closed position by engineer.

I claim:

1. In an apparatus of the character described, a locomotive having thereon an electric motor, a reservoir for compressed air, a pipe leading from the reservoir, a valve for said pipe, controlled by the electric motor, a pneumatic chamber to which said pipe leads, a piston in said chamber operatively connected with a locomotive controlling mechanism, electric means comprising a circuit in which a current is established under danger conditions, and including a device subject to the operation by such current circuit for controlling said electric motor, a steam pipe, connecting into said air pipe and having a valve therefor, means for exerting a pressure in the opening direction on said valve, and means whereby said pressure exerting means is controlled by the air pressure in the reservoir.

2. In an apparatus of the character described, a locomotive having thereon an electric motor, a reservoir for compressed air, a pipe leading from the reservoir, a valve for said pipe, controlled by the electric motor, a pneumatic chamber to which said pipe leads, a piston in said chamber operatively connected with a locomotive controlling mechanism, electric means comprising a circuit in which a current is established under danger conditions, and including a device, subject to operation by such current circuit, for controlling said electric motor, a steam pipe, connecting into said air pipe, beyond the reservoir and having a valve therefor, means for exerting a pressure in the opening direction on said valve, means whereby said pressure exerting means is controlled by the air pressure in the reservoir, and a check valve provided in the pipe leading from the reservoir between the latter and the junction with said pipe of the steam pipe.

Signed by me at Springfield, Mass., in presence of a subscribing witness.

ROBERT CECCHINI.
